UNITED STATES PATENT OFFICE.

DALLAS D. WERTZBERGER, OF TULSA, OKLAHOMA.

WELL-DRILLING DERRICK.

Application filed July 19, 1924. Serial No. 727,033.

This invention relates to well drilling derricks, with particular reference to the type known as a cable drilling rig.

Owing to the commonly inaccessible locations of such rigs, and the difficulty of erection, such derricks are commonly constructed of wood with bracing applied thereto in an endeavor to neutralize the vibration of the structure under the heavy loading and impact stresses it is subjected to in drilling service. The varying and intermittent nature of the loading tends to loosen up all the fastenings and it is not an uncommon happening for parts of the derrick to work loose and drop impairing the structure and exposing the workers to possible injury. It is accordingly an object of this invention to provide improved bracing means for a derrick so constructed that the parts will be held against working loose.

It is a further object of this invention to provide an improved joint between the legs and the sills of the derrick whereby the alignment of the derrick may be restored after settlement by jacking up the sill timbers under the proper corners and blocking or wedging the legs, thus eliminating the labor and danger of digging a space under the legs themselves to permit placing a jack thereunder.

It is also an object of this invention to provide diagonal bracing comprising rods having right and left hand threaded ends screwing into nuts held in brackets, the intersecting points of each pair of diagonal braces being clamped together to eliminate individual vibrations that might tend to unscrew the rods.

It is another object of this invention to provide an improved derrick top or deadwood adapted to rigidly support the cable sheave.

Other and further important objects of this invention will be apparent from the disclosures in the specification and the accompanying drawings.

This invention (in a preferred form) is illustrated in the drawings and hereinafter more fully described.

On the drawings:

Figure 1 is a front elevation of the walking beam side of a complete derrick with some details omitted because of the necessarily small scale of the drawing.

Figure 2 is a side elevation of the lower part of the derrick.

Figure 3 is an enlarged fragmentary elevation of half the panel through which the walking beam projects.

Figure 4 is a fragmentary plan of the derrick top.

Figure 5 is a perspective drawing of the joint between the legs and sill timbers.

Figure 6 is an enlarged section on the line 6-6 of Figure 3.

Figure 7 is an enlarged section on the line 7-7 of Figure 3.

Figure 8 is an enlarged fragmentary elevation of the top panel joint shown in Figure 3.

Figure 9 is an enlarged partial section on the line 9-9 of Figure 1.

Figure 10 is an enlarged elevation of the tie rod bracket at the center of the strut for the walking beam aperture.

Figure 11 is an enlarged fragmentary elevation of the bottom tie rod leg bracket of Figure 3.

Figure 12 is a section on the line 12-12 of Figure 11.

Figure 13 is an enlarged fragmentary elevation of the lower bracket shown in Figure 8.

Figure 14 is a section on the line 14-14 of Figure 13.

Figure 15 is a section on the line 15-15 of Figure 3.

Figure 16 is a section on the line 16-16 of Figure 1.

Figure 17 is a section on the line 17-17 of Figure 1.

Figure 18 is a fragmentary plan view of a corner of the derrick top with parts broken away.

Figure 19 is an enlarged section on the line 19-19 of Figure 1.

Figure 20 is an enlarged section on the line 20-20 of Figure 19.

Figure 21 is a fragmentary elevation showing the top bracket.

Figure 22 is a section on the line 22-22 of Figure 21.

Figure 23 is a section of a modified form of tie rod nut.

As shown on the drawings:

The derrick in general comprises four upstanding standards or legs 25 which converge toward the top to form a platform 26, commonly called the deadwood, to support the drilling cable sheave and the sand line 110 sheave if one is used. The lower ends of the legs 25 are rabbeted as at 27 in Figure

5 to receive a pair of parallel sills 28. A second pair of sills are placed at right angles to the first pair and the whole securely bolted together. Because of the rabbeted sills, the 5 legs are in effect partially supported thereby so that settling of the structure due to the loading thereof is not so likely to throw the derrick out of line with the drill hole, and if such a displacement occurs the 10 sills may be jacked up to permit rearrangement of the usual blocking under one or more of the derrick legs. The joints between the legs and sills are further reinforced by diagonal struts 29 from each leg to 15 each sill.

A plurality of cross members 30 serve to tie the legs together at different heights to eliminate buckling of the legs under the load. These cross members serve to divide 20 the derrick into panels, which are diagonally braced each way by rods 31 having right and left threaded ends engaging in nuts 32 held in anchoring brackets 33 which are provided with lugs 34 adapted to contact one 25 face of the nuts to prevent movement thereof. Figure 8 shows a typical bracket arranged to be bolted over the joint between two cross members 30 and having provision for four bracing rods in two planes. Because of the greater width between the legs in the lower half of the derrick the cross 30 members are preferably reinforced by a bolted in timber 35 abutting against the legs 25.

35 In the panel next above the ground or working platform 36 provision is made for the end of the walking beam by providing a pair of vertical struts 37 connecting intermediate cross-members 38 and inserting 40 short filler timbers 39 to take the compressive strain of short tie rods 40 arranged to brace the panel without obstructing the opening between the struts 37. Anchoring brackets 41 of Figure 10 are used on the 45 struts adjacent the filler timbers 39, the upper rods from this bracket leading to brackets 42 shown in Figures 8 and 13; and the lower rods leading to brackets 43 shown in Figure 11. From these brackets 43 rods lead 50 to brackets located on the leg ends of the filler timbers and thence other rods lead to

the regular panel brackets 33 at the top of this special panel. Wherever two rods 31 cross or intersect a U clamp 44 is used to dampen vibration and prevent loosening of 55 the rods in service.

The nuts 32 used with the rods 31 are preferably provided with a cylindrical section 45 adapted to pass through the apertures in the bracket and thereby prevent damage to the threads of the rods from contact with the apertures under the existing conditions of severe vibration which would quickly batter the threads to such an extent as to prevent 60 subsequent tightening of the rods if necessitated by the shrinkage of the wooden members of the derrick upon exposure. In the modification of Figure 23 the nut and bushing 45 is not held from rotation by lugs on the bracket but is clamped by a locking nut 65 on the rod.

The structure of the derrick top or dead-wood 26 is illustrated in Figures 18 to 20. The tops of the legs 25 are cut off to form a plane surface, and a bolted framing 46 is 70 secured thereto. The deadwoods 47 proper are bolted to two of the side members of this framing to form a sheave bearing supports. The rods bracing terminates in 75 brackets 48 shown in Figure 21 which are applied to the corners of the framing 46 to hold it in place on the legs 25.

I am aware that many changes may be made, and numerous details of construction may be varied through a wide range without departing from the principles of this invention, and I therefore do not purpose limiting the patent granted hereon, otherwise than necessitated by the prior art.

90 I claim as my invention:

Diagonal bracing for derrick legs comprising anchoring brackets secured to said legs and having apertures, nuts having integral bushings formed thereon and extending through said apertures, diagonal rods having right and left handed threads engaging said nuts, and lugs on the brackets engaging said nuts to prevent rotation thereof.

95 In testimony whereof I have hereunto subscribed by name.

DALLAS D. WERTZBERGER.
